UNITED STATES PATENT OFFICE.

MOSES VAN SLYKE, OF CLARKSVILLE, IOWA; W. L. ASHER ADMINISTRATOR OF SAID
MOSES VAN SLYKE, DECEASED, ASSIGNOR OF ONE-HALF TO JOSEPH VAN SLYKE, OF
CLARKSVILLE, IOWA.

BURIAL VAULT.

Application filed January 27, 1922. Serial No. 532,272.

To all whom it may concern:

Be it known that I, MOSES VAN SLYKE, a citizen of the United States, residing at Clarksville, in the county of Butler and 5 State of Iowa, have invented certain new and useful Improvements in Burial Vaults, of which the following is a specification.

This invention relates to burial vaults, and more particularly to vaults formed of cement, concrete or similar material.

An object of the invention is the provision of a vault of simple construction that can be manufactured inexpensively.

A further object is the provision of a 15 vault provided with suitable sealing means to exclude air, moisture, and the like.

In the accompanying drawings, I have shown several embodiments of the invention. In this showing:

20 Figure 1 is a side elevation of one form of the invention,

Figure 2 is a vertical sectional view on line 2—2 of Figure 1,

25 Figure 3 is a perspective view taken in the plane of Figure 2,

Figure 4 is a similar view of a slightly modified form, and,

Figure 5 is a detail sectional view of the 30 form shown in Figure 4.

Referring to the drawings, the reference 35 numeral 1 designates the bottom of the vault which, as shown, is made curved in cross-section, and is provided with side and end flanges 2. These flanges are provided with a flat upper faces 3, having grooves 4 formed therein. The body of the vault consists of a curved top 5, having sides and ends 6 depending therefrom. The lower surfaces of the sides and ends are flat, as at 7, to fit 40 the top 3 of the flanges, and these flat sides are provided with ribs 8 adapted to be received in the grooves 4. When the vault is closed, the meeting edges may be covered with suitable cement or other similar material to provide an air-tight closure. The 45 sides may be provided with panels 9, as

shown. A re-enforcing strip 10 may be arranged within the top, the re-enforcing strip being provided with depending portions 11, extending down the sides and ends 50 of the body.

In the form of the invention shown in Figures 4 and 5 of the drawings, the lower edge of the side is provided with a projecting portion 12 adjacent the outside. The 55 bottom is cut away, forming a recess 13 adapted to receive this projecting portion.

By means of the construction herein described, an air-tight and moisture proof vault may be obtained. The simplicity of 60 construction reduces the cost of manufacture to a minimum and the provision of a curved top and a curved bottom adds materially to the strength of the vault.

It is to be understood that the forms of 65 my invention herewith shown and described are to be taken as preferred examples of the same, and that various changes in the shape, size, and arrangement of parts may be resorted to without departing from the 70 spirit of the invention or the scope of the subjoined claim.

Having thus described my invention, I claim:

A burial vault comprising a curved top, 75 side and end walls depending therefrom, and a curved bottom on which said side and end walls are adapted to rest, said bottom being provided with a peripheral flange having a flat upper face adapted to receive 80 the lower face of the side and end walls, one of said faces being provided with a longitudinal groove, and a rib formed on the other face and adapted to be received in said groove. 85

In testimony whereof I affix my signature in presence of two witnesses.

MOSES VAN SLYKE.

Witnesses:

B. WANSLEY,
FLOYD L. ASHER.
